UNITED STATES PATENT OFFICE.

HARRY W. WHIPPLE, OF KANSAS CITY, MISSOURI.

DESIGN FOR A PLAQUE.

61,219.

Specification for Design. Patented July 11, 1922.

Application filed March 24, 1920. Serial No. 368,415. Term of patent 3½ years.

To all whom it may concern:

Be it known that I, HARRY W. WHIPPLE, a citizen of the United States, and a resident of Kansas City, in the county of Jackson and State of Missouri, have invented a new, original, and ornamental design for a Plaque, of which the following is a specification, reference being had to the accompanying drawing, forming part thereof.

The said drawing of the plaque is represented in two figures as follows:

Figure 1 is a face view of a plaque embodying my new design.

Figure 2 is an upper edge view of the same.

The plaque is of rectangular form with recessed and rounded corners and with its

edges including the corners beveled downwardly and outwardly from its face. A panel is formed on the face of the plaque by a raised bead which projects from said plaque and in contour is approximately the same as the marginal contour of the plaque.

Exterior to the bead, the plaque is stippled upon its face and upon its beveled edges, as clearly shown.

I claim:

The ornamental design for a plaque, as shown and described.

HARRY W. WHIPPLE.
